United States Patent Office

Des. 227,899
Patented July 24, 1973

227,899

DATA COMMUNICATIONS UNIT

Donald M. Genaro, Haworth, N.J., Arthur A. Hagstrom,
Hoffman Estates, Ill., and Gordon Sylvester, Jamaica,
N.Y., assignors to Teletype Corporation, Skokie, Ill.

Filed Jan. 17, 1972, Ser. No. 218,664

Term of patent 14 years

Int. Cl. D14—02

U.S. Cl. D26—5 C

FIG. 1

FIG. 2

FIG. 3

FIG. 4

FIG. 5

FIG. 1 is a perspective view taken from the front and left side of a data communications unit embodying our new design;

FIG. 2 is a top view thereof;

FIG. 3 is a rear view thereof;

FIG. 4 is a front view thereof; and

FIG. 5 is a right side view thereof.

We claim:

The ornamental design for a data communications unit, substantially as shown.
